No. 37,419.

Patented April 25, 1905.

UNITED STATES PATENT OFFICE.

FELIPPE A. BROADBENT, OF BALTIMORE, MARYLAND.

DESIGN FOR A MANTEL.

SPECIFICATION forming part of Design No. 37,419, dated April 25, 1905.

Application filed March 16, 1905. Serial No. 250,477. Term of patent 7 years.

To all whom it may concern:

Be it known that I, FELIPPE A. BROADBENT, a citizen of the United States, and a resident of Baltimore, Maryland, have invented a certain new, original, and ornamental Design for a Mantel, of which the following is a specification, reference being had to the accompanying drawing, forming part thereof.

The figure is a front view of a mantel, showing my new design.

I claim—

The ornamental design for a mantel as shown.

FELIPPE A. BROADBENT.
